NIGHTGOWN

Norman Grober, New York, N. Y.

Application November 19, 1949, Serial No. 128,368

1 Claim. (Cl. 2—73)

1

This invention relates to improvements in ladies' undergarments and more particularly to improvements in the construction of shoulder straps or shoulder suspension members used in connection with nightgowns, slips, brassières, etc. Such shoulder straps are conventionally made of non-elastic material at present time, do not adjust themselves to the wearer's comfort and will not conform to the movements of the body in walking, resting, sleeping, stretching, etc. It obviously is impossible to adjust these straps each time it would become necessary. The result is in many instances a broken shoulder strap, which can become very embarrassing to the wearer, or discomfort at the top of the shoulders, where the shoulders support the garment, or the seams may pull or break. Furthermore, the straps have a tendency to slip off the shoulder.

It is a main object of this invention to elasticize the shoulder straps of an undergarment.

It is a further purpose of this invention to provide shoulder straps on ladies' garments which will overcome the above-mentioned disadvantages.

It is another object of this invention to provide shoulder straps, which will have one or more elastic elements incorporated therein.

It is still another object of this invention to provide aesthetic-looking shoulder straps for undergarments, which will "give" under all conditions, and which will add to the good appearance of the garment.

These and other objects of the invention and the means for their attainment will be more apparent from the following detailed description, taken in connection with the accompanying drawing, illustrating certain embodiments of which the invention may be realized, and in which:

Fig. 1 illustrates a typical example of a garment, such as a night gown, according to the invention, which is worn with complete comfort under many changing conditions, while the person is lying down;

Fig. 2 is a partial upper view of a night gown having shoulder straps embodying two elastic elements in each shoulder strap;

Fig. 3 is a sectional view of a shoulder strap taken on line 3—3 of Fig. 2;

Fig. 4 is a partial upper view of a slip having narrow shoulder straps with one elastic element in each strap, and

Fig. 5 is a sectional view through a shoulder strap taken on line 5—5 of Fig. 4.

Referring now in detail to the accompanying drawings, there is shown in Fig. 1 a lady 10, wear-

2

ing a night gown 11. The lady is shown on a bed or couch 12 in a reclining position, resting against pillows 13. Her arms 14 are shown as placed above her head, this providing a condition requiring the utmost in comfort, especially at the shoulders 15 with the shoulder straps 16. Resting thus on a couch or bed, it will be seen that any stretching of the upper body, or stretching of the arms as shown, will cause a pull on the shoulder straps, while the weight of the body resting within the garment will prevent the garment from giving or adjusting. Conventional straps will make the position shown very uncomfortable in a short time without the person having to resort to pulling up of the garment.

As illustrated in Fig. 2, there is shown such a garment 11, having the bodice 20 and the gown portion 21. The shoulder straps 16 consist of the center portion 22 of shirred material, the lace edging 23 and elastic bands 24 sewn in at the juncture 25 of the center portion 22 and the edging 23. Stitches 26 are applied preferably while the strap is in stretched condition. The shoulder straps 16 are conventionally secured to the garment as at 27. In Fig. 2, lace material is shown for the edging 23, but it is understood, that other material, contrasting or otherwise, may be used. Figs. 4 and 5 illustrate shoulder straps 30 in conformity with the invention. In this embodiment of the invention, each shoulder strap 30 is shown with one elastic element 31 in the center of a suitable shirred ribbon or band 32, secured by stitches 33. In this case, again, the shoulder straps 30 are secured in any conventional manner at 34 to the garment 35.

Referring to the application of the invention to a nightgown, when the sleeper twists and turns, then only the shoulder members of the gown will follow the twisting of the body and conform to that part of the body in contact therewith, without affecting or stretching the remainder of the gown. That is, the elastic members of the shoulder straps have a combined resistance to stretching sufficient to support the weight of the gown and elongate only in response to the application of additional tension thereto. The most common disadvantage of nightgowns is the pulling at the straps or shoulder members where they are attached to the body or bodice of the gown. By elasticizing the shoulder strap, the latter will stretch and relieve the straining points.

The shoulder straps may be entirely elasticized, or a portion of each thereof only may be elasticized, for example, the front, rear or top center

55

section or portion of each strap member, only, may be elasticized and the remainder thereof may be non-elastic.

The foregoing disclosure is to be regarded as descriptive and illustrative only, and not as restrictive or limitative of the invention, of which obviously an embodiment may be constructed including many modifications without departing from the general scope herein indicated and denoted in the appended claim:

Having thus described my invention, what I claim as new and desire to secure by Letters Patent, is:

A nightgown comprising a body provided with a bodice and a unitary skirt, and shoulder straps attached to said bodice, each of said shoulder straps including an elongated, flexible, shirred intermediate portion and spaced longitudinal elastic members secured to the sides of said shirred portion by stitching with said elastic members in a stretched condition, said elastic members being normally formed with contracted

lengths positioning the nightgown on the wearer and with a combined resistance to stretching sufficient to support the weight of the nightgown without stretching so that said straps elongate

5 in response to increased tensioning thereof, said elastic members and said shirred intermediate portion being secured at their ends adjacent the top of the front and back portions of said bodice.

NORMAN GROBER.
